UNITED STATES PATENT OFFICE

RALPH A. SQUIER, OF TETON, WASHINGTON

ADJUSTABLE BOX FORM

Application filed January 23, 1930. Serial No. 422,877.

This invention relates to forms for making wooden boxes, the sides and bottom of which are nailed to the ends or heads and particularly to a form of this character designed for supporting the heads in place while the bottom or sides are being nailed to the heads.

One of the objects of the invention is to provide a form of this character so designed that the bottoms or side panels of the box may be accurately alined with the ends of the heads without any care being taken on the part of the operator.

A further object is to provide means whereby the cleats of a box may be accurately alined with the outside faces of the heads and outside edges of the side or bottom panels without the necessity of particular care on the part of the operator.

20 A further object is to provide a box form of this character having opposed vertical supporting members, one of which is resiliently supported so as to permit the easy insertion of the box heads and eliminate any chance of the box binding within the form and preventing its ready removal and reinsertion in another position.

Another object is to provide resiliently actuated head clamping members which are 30 provided with adjustable stops, limiting the inward movement of the clamping members against the box heads so as to prevent any binding action.

Other objects will appear in the course of 35 the following description.

My invention is illustrated in the accompanying drawings, wherein:—

Figure 1 is a front elevation of a box form constructed in accordance with my invention;

Figure 2 is a top plan view thereof;

Figure 3 is a section transversely across the box form through the middle thereof;

Figure 4 is a fragmentary rear elevation 45 of one end of the box form;

Figure 5 is a vertical sectional view through a box and through one end of the box form;

Figure 6 is a detailed vertical section on 50 the line 6—6 of Figure 2;

In the drawings, I have shown my box form arranged for the formation of a pair of boxes in order to illustrate my invention.

Referring to these drawings, 10 and 10^a designate two parallel supporting members constituting the base of the form. These supporting members are provided preferably with the angular attaching members 11 whereby the form may be engaged with the bench, such a bench as is shown in my prior application, Serial No. 365,438 filed on May 23, 1929.

Rigidly attached to the member 10 are the rods or bolts 12 which extend transversely across the form adjacent the bottom thereof and pass through openings in the opposite member 10^a, this end of the rod 12 being screw-threaded at 13 and provided with the nuts 14 whereby the member 10^a on one side may be adjusted nearer to or further from the member 10 on the opposite side.

The members 10 and 10^a are preferably metallic and cast with the member 10 or otherwise rigidly connected thereto are the uprights 15. Associated with the member 10^a are the uprights or standards 15^a through which the bolts 12 may pass as shown in Figure 1, though it is to be understood that the standards 15^a might be cast with the base members 10^a. Mounted upon the standards 15^a is a plate 16^a whose outer edge face is beveled as best shown in Figure 2. This plate 16^a is spaced from the upper face of the corresponding member 10^a. Opposed to the member 16^a is a corresponding plate 16 of the same form as the plate 16^a. This is carried by bolts 17 on the standards 15, the bolts carrying the nuts 18, these nuts being adjustable to limit the inward movement of the plate 16 with reference to the corresponding standards 15.

Attached to the member 10 by a bolt 19^a and extending upward therefrom is a preferably metallic arm 19 carrying at its upper end the coiled compression spring 20, which bears against the plate 16 and urges this plate inward but permits the plate to be moved outward against the action of the spring. The plates 16 and 16^a are shorter than the members 10 and 10^a and do not ex-

100

tend rearward as far as the members 10 and 10a. The mounting of the end plate 16 shown in Figure 2 and heretofore described is an important feature of my invention. The end plate 16 is supported at four points by four bolts 18, these bolts being fastened rigid with the end plate, but fitting loosely in holes made in the standards 15. The outer ends of these bolts carry lock nuts so that when the spring 20 forces the plate 16 inward, these lock nuts will rest against the standards 15. These lock nuts are designed to be adjusted preferably at the factory and before the box form is sent to the user so that the plate 16 is truly vertical. When the spring 26 forces the plate 16 inward. These four bolts, therefore, always hold the plate 16 in a truly vertical position and at right angles to the longitudinal axis of the form. These lock nuts merely limit the inward movement of the end plate 16. This inward movement of the end plate 16 is designed for the purpose of facilitating the turning of the box when the box is being constructed in case the box end is warped or untrue. The plate 16 is held in place, that is, forced inward by the spring 20 which bears against the tension plate 19, this plate being held in place at its lower end by means of the nut 19a shown in Figure 4 and by rotating this nut the degree of tension on the plate may be adjusted. The pressure on this plate 16 exerted by the spring 20 and the tension plate is also greater than the pressure of the spring 29 of the corresponding clamp 30. With this construction, assuming that the box material is warped or untrue, then when the operator turns the box in this form, the plate 16 and the clamp 30 will both give and allow crooked box material to turn freely. By having the tension on spring 20 greater than that of spring 29, this end plate 16 will always assume its proper position as soon as the turning of the box is completed and the four point suspension of plate 16 insures an equal pressure on the whole surface of the box end. With this arrangement, a box end which varies in thickness, say from two inches thick on one side to one inch thick on the opposite side, will be held firmly against plate 16 by clamp 30. Thus all variations in box materials will be on the inside of the box and thus making a very true and neat job.

Box ends are made to a large extent out of two pieces held together with corrugated fasteners driven in by machine and often these fasteners are not driven clear in or bent so that they interfere with the turning of the box in the form. In this two piece construction, of the box end, it is quite common to run into a box end that has two different thicknesses of lumber and thus there is a shoulder on the end and that gives a great deal of bother to the box maker. Furthermore, in these box ends oftentimes, a loose nut has worked out

of place and this causes bother. In box forms known to me and in use, the end plates are oftentimes so narrow that one of these obstructions will be below the lower edge of the end plate and thus when the operator goes to turn the box, this obstruction will catch on the lower edge of the end plate. In my construction, the end plates cover most of the box end and the operator is thus not bothered with these faults in material and furthermore, as explained above, one of the box ends is resiliently held in position so as to compensate for different thicknesses of material.

Mounted upon the rear ends of the members 10 and 10a are the uprights 21 and 21a. These uprights may be cast with the members 10 and 10a or otherwise rigidly engaged therewith. One of these uprights is shown in detail in Figure 4. Each upright carries upon its upper end, the plate 22 which is cut away at 23, the inner margin of the plate being upwardly extended as at 24.

Attached to this upward extension is a metallic bar or strip 25 which is adjustably mounted upon the extension bar 24 by means of the bolt 26, this bolt being adapted to pass through any one of a number of perforations 27 in the extension and the bolt being surrounded as shown in Figure 3 by a coil spring 28. Preferably the extension 24 is slightly concavo-convex transversely and the bar is also slightly concavo-convex so as to fit within the extension 24.

It will be seen that the bar 25 may be raised or lowered or may be turned into angular relation to the extension 24. Each of the plates 22 is supported upon the standard or upright 21 or 21a by means of bolts 28 which pass through any one of a number of bolt holes 28a so that the plate 22 may be raised or lowered with reference to the corresponding upright 21.

Bolted to the inner margin of each plate 22 is a spring hinge designated generally 29. One leaf of this hinge is bolted to the corresponding plate 22, the other leaf of the hinge being bolted to a clamp 30, shown particularly clearly in Figure 2. This clamp is bowed inward and is adapted to be urged against the inner face of the head of a box and hold the head of the box clamped firmly between the clamp 30 and the corresponding end member 16 or 16a. The inner end of the clamp (see Figure 2) is shown as being provided with an outwardly extending angular flange 31 at the butt end of the clamp and extending through the plate 22 is an adjustable stop 32 shown in detail in Figure 6 which is in the form of a screw and whose inner end bears against the confronting face of the flange 31. By rotating this screw in one direction or the other, this stop formed by the screw may be adjusted to thereby adjustably limit the inward movement of the clamp 30.

Each plate 22 is so mounted that its outer

edge is in alinement with the inner face of the corresponding end plate 16 or 16^a and each plate 22 extends slightly above the upper edge of the member 16 or 16^a. The upper edge of each of the members 16 or 16^a is formed with openings 33 as shown in Figure 5 which extend downward through the end member and then laterally outward, these openings being designed for the reception of nails 34 passing through a wooden cleat 35 which forms the top edge of the plates 16 or 16^a. When these wooden cleats or facing pieces have become damaged, the nails 33 may be readily withdrawn and new cleats put in place. These wooden facing pieces or cleats are used upon the upper edges of the plates 16 or 16^a for the purpose of preventing the blows of a hammer being received directly against the metallic end plates, thus providing a cushion for the hammer and a facing piece which may be readily removed when it is damaged to permit a new facing piece to be put in place. These cleats or facing pieces 35 also form guides for the cleats of the box as shown in Figure 5.

For the purpose of permitting this box form to be used for boxes of various sizes and shapes, I provide auxiliary supporting members designated as 36 and 36^a and shown particularly in Figures 1 and 2. These auxiliary members are each angular in cross section to provide a shoulder 37 and these members 36 and 36^a may be either dispensed with entirely or disposed, as illustrated in Figure 1, with the shoulders 37 in vertical planes or these members may be disposed with the shoulders 37 in horizontal planes and disposed beneath the lower edges of the members 16 and 16^a. The auxiliary support 36^a is preferably formed with recesses or grooves 38 to receive the standards 15^a when the member 36^a is disposed in what may be termed a vertical position.

The member 36, however, is not formed with any grooves but is disposed flat against the standards 15. A rod 39 or dowel has its ends inserted in openings extending through the shoulders 37, when the auxiliary supports 36 and 36^a are disposed in a horizontal plane and this rod is surrounded by a coil spring 40 which urges the auxiliary supports 36 and 36^a away from each other. Each of the auxiliary supports is also formed with an opening 41 in the back of the support into which the ends of the dowel or rod 39 may be inserted when these auxiliary supports are disposed in a vertical plane.

In the use of this form, the heads A of the boxes are disposed against the end plates 16 and 16^a as shown in Figure 5 and between the end plate 16^a and the clamps 30. In this position of the parts, the upper edge of the head A is level with the upper edges of the plates 16 and 16^a. One of the bottom panels B is then disposed upon the top of the

heads A and is guided into this position without any special care on the part of the operator by the cleats 35 as shown in Figure 5. This bottom is forced back until it strikes the limiting bars 25 or the plates 22, the inner faces of the limiting bars being flush with the inner faces of the plates 22 and when the element B has been forced back against these plates 22, the operator knows that the edge of the element B is in alinement with the edges 75 of the elements A.

A cleat C may then be disposed upon the top of the element B at the ends thereof as shown in Figure 5 and in putting this element C in place, the operator forces the end of it 80 against the upstanding portion of the corresponding plate 22 and against the inside face of the cleat 35 and thus without any special care, the cleat C is alined properly with the panel B and with the heads A. 85

The panel B, the cleats C, and the heads A may then be nailed together by nails driven through the cleats C. It will be noted that the cleat C will be under these circumstances above the adjacent portion of the adjacent 90 plate 22 and the most adjacent metallic part which will be sufficiently spaced from the point where the nails are to be applied as to prevent the operator from striking this part 25 with the hammer, any accidental blows 95 from a hammer being received upon the wooden cleat 35 forming the upper edge facing for the plates 16 or 16^a.

The above description applies to the operation of placing bottoms upon the heads and 100 nailing the bottoms thereto and applying sides to the heads. The end plates 16 and 16^a only hold the heads in place and do not aline the sides with the heads as they do when applying bottoms. At least this is the case in 105 the formation of apple boxes as apple box heads are 10½ inches deep by 11½ inches wide. Therefore, when the operator applies the heads, he places the side on heads with one hand, pushes the side back against the parts 24 and alines the ends of the sides with the outer surfaces of the heads with the other hand. In making apple boxes, the auxiliary elements or supports 36 and 36^a are not used, but the heads of the boxes are disposed directly on the supporting members 10 and 10^a. The members 25 and the supporting members 36 and 36^a are designed primarily for use in 110 making pear boxes, a pear box head being the same width as the apple head but the depth of the pear head being about 1½ inches less than the apple head. Therefore to make pear boxes on this form, the auxiliary members 36 and 36^a are disposed in a horizontal position. The pear box heads are then inserted between 115 the members 30 and 16 and 30 and 16^a ready to receive the sides. The pear heads in this position, because they rest on the supporting members 36 and 36^a are about 1½ inches higher than the top of the extension 24. 120

125

130

Therefore, in order to have stops to aline the sides of the pear box to the heads, it will be necessary to shift the parts 25 upward to meet this requirement.

- 5 These parts are convexed so that the springs 28 will hold the part 25 in an upright position. The attaching leaf of the hinge 29 is adjustable upward and downward on the corresponding plate 22 by providing apertures 10 29^a in which the bolts for the hinge 29 may be adjusted. This adjustment is necessary in the making of some boxes. The plates 22 are also adjustable up and down upon the standards 21 and 21^a as shown in Figure 4. 15 The tension of the spring 20 is adjustable by the bolt 19^a shown in Figure 3 which holds the metallic arm 19 in place.

This adjustable box form is so constructed that it is not necessary to use an elaborate bench to do good work on as the weight of itself is sufficient to enable the operator to drive the nails home with the least exertion. This form can be readily moved from place to place which is not the case where the bench 25 and form are combined. Another improvement present in my construction which is not to my knowledge found in any other box form is the means whereby the form is fastened down to the bench. Most of the forms are 30 fastened on all four corners while I simply use two brackets 11 at the middle of the parts 10 and 10^a. By so doing, the bench to which this form is fastened may warp quite a bit before it will pull this form out of shape. By 35 the use of the auxiliary members 36 and 36^a, my form may be used for the making of apple, peach, pear and other boxes, suit-cases, cannery lugs and cannery packing cases. The auxiliary members 36 and 36^a may be cast 40 in any dimension or shape to accommodate most any shaped-box. This form is preferably made of metal and, therefore, will last indefinitely. It will not warp or loose its adjustments. Without the auxiliary elements 45 36 or 36^a, this form is made to make apple boxes and cannery packing cases and any other boxes of about these dimensions.

Attention is particularly called to the means whereby I secure the rod 12 to the member 10 as shown in Figure 1, this rod being permanently engaged with the member 10 by expanding the rod and forcing the rod into the member 10 and then overturning the rod. By this means, the rod cannot become loose 55 by hammering on the bench. Where lock nuts are used at opposite ends of the rods 12 for engaging the members 10 and 10^a constantly hammering on the bench will eventually loosen the lock nuts and allow the form 60 to loose its adjustment.

My form is an "open-back" form, that is, the two lateral elements of the form are not connected above the base of the form by means of strips or like elements and with an 65 open-back form there is no limit to the ad-

justment that may be made in the length of the form, the limit only depending upon the length of the bolts 12.

I am aware of no other form which has been devised or is on the market which will 70 make more than apple or pear boxes, whereas my form is adaptable not only for the making of apple and pear boxes but to a large number of other boxes as well.

While I have illustrated certain details of construction and arrangement of parts which I think to be particularly effective, I do not wish to be limited to these details as obviously many changes might be made therein without departing from the spirit of the invention as defined in the appended claims. 75 80

I claim:—

1. A box form including parallel spaced horizontal head supports, vertical end plates carried by the head supports, one of said plates being yieldingly mounted and being resiliently urged toward the other plate, rear vertically disposed plates carried by the supports extending at right angles to the vertical end plates, and spring actuated head clamps carried by said last named plates and resiliently urged toward the corresponding end plates. 85 90

2. A box form including parallel spaced horizontal head supports, vertical end plates carried by the head supports, one of said plates being yieldingly mounted and being resiliently urged toward the other plate, rear vertically disposed plates carried by the supports extending at right angles to the vertical end plates, and spring actuated head clamps carried by said last named plates and resiliently urged toward the corresponding end plates, the plates supporting the head clamps being adjustable vertically with relation to the head supports. 95 100

3. A box form including parallel spaced horizontal head supports, vertically disposed end plates operatively carried by the supports, rear vertically disposed plates operatively carried by said supports and extending at right angles to the vertical end plates, and spring actuated head clamps carried by the last named plates and resiliently urged each toward its corresponding end plate, and adjustable means for limiting the inward movement of said clamps. 110 115

4. A box form including parallel spaced horizontal head supports, vertically disposed end plates operatively carried by the supports, rear vertically disposed plates operatively carried by said supports, and spring actuated head clamps carried by the last named plates and resiliently urged each toward its corresponding end plate, and adjustable means for limiting the inward movement of said clamps, including a flange on each of the clamps and a screw extending through the plates supporting the clamp and engaging said flange. 120 125 130

5. A box form including parallel spaced horizontal head supports, vertically disposed end plates carried by the supports, standards extending upward from the rear ends of said supports, vertically disposed rear plates adjustably mounted upon said standards for vertical adjustment, and spring actuated head clamps carried by the last named plates and resiliently urged each toward the corresponding end plate, each of said clamps being outwardly curved at its free end. 70
6. A box form including parallel spaced horizontal head supports, vertically disposed end plates carried on the said supports and extending parallel therewith, the rear vertically disposed plates operatively mounted upon said supports and constituting means limiting the rearward movement of box heads disposed against the end plates, and wooden cleats removably disposed upon the upper edges of the end plates and extending above the adjacent end corners of the rear plates. 80
7. A box form including parallel spaced horizontal head supports, standards mounted thereon, vertically disposed end plates carried by the standards and extending parallel to the outer edges of said supports, standards extending upward from the rear ends of the supports, rear vertically disposed plates adjustably carried upon said standards and acting to limit the inward movement of box heads disposed upon said supports and against the end plates, spring actuated head clamps mounted upon said rear plates and resiliently urged each toward its corresponding end plate, each rear plate along its inner margin being extended upward, a bar pivotally mounted upon the inner face of said extension of each rear plate, and means frictionally holding said bar against movement from a rotatably adjusted position. 90
8. A box form including parallel spaced horizontal head supports, standards mounted upon the head supports, vertically disposed end plates carried by the standards and disposed with their lower edges in spaced relation to the upper edges of the head supports, head clamps disposed opposite each of said end plates and resiliently urged each toward its corresponding end plate, and auxiliary head supports adapted to be mounted upon and rest on the main head supports and resilient means urging said auxiliary supports away from each other. 100
9. A box form including parallel spaced horizontal head supports, standards mounted upon the head supports, vertically disposed end plates carried by the standards and disposed with their lower edges in spaced relation to the upper edges of the head supports, head clamps disposed opposite each of said end plates and resiliently urged each toward its corresponding end plate, and auxiliary head supports adapted to be mounted upon and rest on the main head supports, each of the auxiliary supports being angular in cross section to provide a shoulder and each of said supports being adapted to be disposed with the face of the shoulder either in a horizontal or a vertical position, with the supports disposed beneath the lower edges of the end plates, and resilient means urging said auxiliary supports against the standards. 110
10. A box form including parallel spaced horizontal head supports, standards mounted upon the head supports, vertically disposed end plates carried by the standards and disposed with their lower edges in spaced relation to the upper edges of the head supports, head clamps disposed opposite each of said end plates and resiliently urged each toward its corresponding end plate, and auxiliary head supports adapted to be mounted upon and rest on the main head supports, each of the auxiliary supports being angular in cross section to provide a shoulder and each of said supports being adapted to be disposed with the face of the shoulder either in a horizontal position or a vertical position, with the supports disposed beneath the lower edges of the end plates, and resilient means urging said auxiliary supports against the standards. 120
11. A box form including parallel spaced horizontal head supports, standards mounted upon the head supports, vertically disposed end plates carried by the standards and disposed with their lower edges in spaced relation to the upper edges of the head supports, head clamps disposed opposite each of said end plates and resiliently urged each toward its corresponding end plate, and auxiliary head supports adapted to be mounted upon and rest upon the main head supports, each of the auxiliary supports being angular in cross section to provide a shoulder and each of said supports being adapted to be disposed with the face of the shoulder either in a horizontal position or a vertical position, with the supports disposed beneath the lower edges of the end plates, and resilient means urging said auxiliary supports against the standards, and including a rod engageable in the auxiliary supports when the auxiliary supports are disposed either in a horizontal or a vertical plane, and a compression spring surrounding said rod and bearing against said auxiliary supports. 130
12. A box form including parallel spaced horizontal head supports, standards mounted upon the head supports, end plates carried

by the standards, and rods connecting said head supports, all of said rods being rigidly engaged with one of said head supports, the opposite ends of the rods being screw-threaded and passing loosely through the other head support and corresponding standard and nuts on said rods engaging the screw-threaded portions thereof and clamping against the inner face of the last named head support and the outer face of the corresponding standards.

13. A box form including parallel spaced horizontal head supports, vertical end plates carried by the head supports, one of said plates being mounted for limited rectilinear movement toward or from the opposite plate, means resiliently urging said movable plate toward or from the opposed end plate, rear vertically disposed members carried by the support, spring actuated head clamps, one carried by each of said last named members, and springs resiliently urging the clamps toward the corresponding end plates, the spring of the corresponding clamp being less in strength than the spring engaging the end plate.

14. A box form including a base structure, vertical members extending upward from the base, an end plate carried upon the vertical members at one end of the base, a plurality of bolts extending through the vertical members at the other end of the base, the bolts being slidably mounted through said members, an end plate carried by said bolts for rectilinear movement toward or from the last named end plate, a member extending upward from the base exterior to the last named end plate, a compression spring disposed between the last named end plate and said member, spring actuated head clamps operatively supported from the base and disposed inward of each of the end plates, and resiliently urged each toward its corresponding end plate, the spring of the clamp coacting with the movable end plate being less in strength than the strength of the spring urging said end plate inward.

15. A box form including parallel spaced horizontal head supports adjustable toward or from each other, vertical members extending upward from the head supports, vertical end plates carried directly on the end members, rear vertically disposed plates extending at right angles to the vertical end plates, and head clamps carried by the last named plates and resiliently urged toward said end plates whereby the head supports with the end plates and rear plates and head clamps may be freely adjusted toward or from each other.

In testimony whereof I hereunto affix my signature.

RALPH A. SQUIER.
